UNITED STATES PATENT OFFICE.

ELOISE S. ELLIOT, OF NEW YORK, N. Y.

FEED-BAG SUPPORT.

No. 912,548.

Specification of Letters Patent.

Patented Feb. 16, 1909.

Application filed June 1, 1908. Serial No. 435,976.

To all whom it may concern:

Be it known that I, ELOISE S. ELLIOT, a citizen of the United States, and a resident of the city of New York, borough of Manhattan, in the county and State of New York, have invented a new and Improved Feed-Bag Support, of which the following is a full, clear, and exact description.

This invention relates to certain improvements in means for supporting feed bags adjacent the mouths of horses and other animals, and the object of the invention is to provide means whereby the feed bag will be normally held in a given position in regard to 10 the animal's head, but whereby the animal may by lowering its head, draw the bag upward, so that it may reach the feed in the bottom of the bag.

Reference is to be had to the accompanying drawings, forming a part of this specification, in which similar characters of reference indicate corresponding parts in all the figures, and in which—

Figure 1 is a perspective view of a device 25 constructed in accordance with my invention and employed for supporting a horse's feed bag; Fig. 2 is a rear view of a portion thereof, one of the pulleys and its support being shown in section; and Fig. 3 is a perspective 30 view of the pulley support.

My improved supporting mechanism may be used for holding any desired form of feed-bag and does not necessitate any changes in the bag other than the provision of bearings 35 upon opposite sides thereof adjacent the upper edge, said bearings comprising pulleys, rollers, rings or other devices permitting free movement of a cord therethrough.

My improved mechanism is made up 40 primarily of two separate members, one adapted to extend over the horse's head and having at its ends bearings in the form of pulleys or other devices permitting free movement of a cord, and the other comprising a 45 cord, rope, or the like, adapted to connect the first-mentioned member, the feed bag and a portion of the harness, or other substantially fixed point adjacent to, on or about the animal.

In the specific form shown, the first-mentioned member is formed of a strap 10, extending over the back of the horse's head, and at each end of the strap is a pulley support 11, preferably formed of a single piece 50 of sheet metal. The metal is cut to form two oppositely-disposed substantially par-

allel face plates 12, 12, connected together at one side by a spacing piece 13, and connected together at the opposite side by a somewhat shorter spacing piece 14. Each side plate at 60 its upper end is bent inwardly to form a horizontally-disposed portion 15, and each of these portions terminates in an upwardly-extending flange 16. The two flanges are substantially parallel and are spaced apart a 65 distance substantially equal to the thickness of the strap 10. The strap extends between the two flanges and is secured in place in any suitable manner, as, for instance, by a plurality of rivets 17.

Above the connecting piece 14, each of the side plates is provided with a vertically-disposed outwardly-bent flange 18, and at the lower end, one of the side plates is provided with an extension 19, serving as means for 70 the attachment of a rope to the side plate. Intermediate the two side plates there is mounted a pulley 20, the pivot 21 of which is secured to the opposite side plates. The support for the pulley at one end of the strap 75 10, is formed exactly the reverse of the support for the pulley at the opposite end of the strap. In other words, one is designed for use on the right-hand side of the horse's head and the other upon the left-hand side. The 80 hook 19 comes upon the outer side plate, that is, the one away from the horse's head, and the flanges 18 which guide the rope to the pulley, come upon the rear side of the 85 device.

The feed bag 22 is provided upon each side thereof with a pulley 23, preferably held between sheet metal plates 24 riveted to the bag, and connecting the two pulleys and a portion of the harness is a rope or cord 25. 90 One end of the rope is attached in any suitable manner to the hook 19 and extends thence to the front side of the pulley 23 and beneath said pulley. The rope then extends upwardly and crosses the portion extending 95 from the hook 19 to the lower pulley, and passes over the upper pulley 20 from the front side thereof. The rope then extends rearwardly to engagement with any suitable portion of the harness along the back, as for 100 instance, the hook 26. The rope is arranged the same on both sides of the head, and preferably only a single piece of rope is employed, the center of the rope coming at 105 the hook 26.

In the rope, at the rear side of the lower pulley 23, I provide a knot, ball or other

suitable projection 27, for preventing the rope from passing over the pulley but in one direction, and at the rear side of the pulley 20, I provide a second knot, ball or projection 28, for the same purpose. The supporting of the bag in the position indicated in the drawings, is not dependent upon the engagement of the rope with the hook 26, for as the knots or projections 28 cannot pass the upper pulleys, the bag cannot drop even though the horse brings its head rearwardly or extends it upwardly into the air. The knots are so placed that they hold the bag with the horse's mouth adjacent the feed when the desired quantity of feed is placed in the bag. The horse by lowering its head toward the ground, increases the distance between the upper pulleys 20 and the hook 26 and this draws on the cord to raise the bag toward the horse's mouth. The knots or projections 27 and 28 may pass away from the pulleys and permit the bag to be raised, but engage with the pulleys to prevent the bag from being lowered to such an extent as to enable the horse to remove his nose from the bag.

Having thus described my invention, I claim as new and desire to secure by Letters Patent:

30 1. In combination, a feed bag, two upper pulleys adapted to be disposed adjacent opposite sides of an animal's head, supports for each of said pulleys, each of said supports being formed of a single piece of sheet metal 35 having a hook or projection, means adapted

to extend across the back of the animal's head and connecting said supports, pulleys adjacent the upper edge of the bag at the opposite sides, and cords, each having one end thereof secured to the corresponding hook or projection and extending downwardly around the corresponding pulley of the bag, thence over the corresponding upper pulley, and thence rearwardly into engagement with a fixed point. 40

2. In combination, a feed bag, a strap adapted to extend across the back of an animal's head, a pulley adjacent each end of the strap, sheet metal supports for each of said pulleys, each of said supports being formed of a single piece of sheet metal including oppositely-disposed face plates, upwardly-extending flanges for attachment to the strap, and a hook or projection, pulleys upon opposite sides of the bag adjacent the upper edge thereof, and cords, each having one end thereof secured to the corresponding hook or projection and extending downwardly around the corresponding pulley on the bag, thence over the corresponding pulley at the end of the strap, and thence rearwardly into engagement with a fixed point adjacent the animal's back. 45

In testimony whereof I have signed my name to this specification in the presence of 60 two subscribing witnesses.

ELOISE S. ELLIOT.
